TRAP FOR CRAWLING INSECTS

Kozaburo Takimoto, 18492 Durfee Lane,
Villa Park, Calif. 92667

Filed Oct. 21, 1974, Ser. No. 516,435

Term of patent 14 years

Int. Cl. D22—06

U.S. Cl. D22—19

FIG. 4

FIG. 5

FIG. 1 is a perspective view of a trap for crawling insects showing my new design;

FIG. 2 is a left side view, the right side being substantially a mirror image thereof;

FIG. 3 is a front view thereof;

FIG. 4 is a top plan view thereof; and
FIG. 5 is a bottom plan view thereof.

I claim:

The ornamental design for a trap for crawling insects, as shown and described.
